VENETIAN BLIND

William M. Dunn, San Bernardino, Calif.

Application January 14, 1944, Serial No. 518,479

3 Claims. (Cl. 160—177)

This invention relates to improvements in Venetian blinds.

It is the object of this invention to produce a Venetian blind of an improved construction that is especially adapted to be made with metal slats, instead of the ordinary wooden slats.

Another object of the invention is to produce a Venetian blind that shall be very inconspicuous when in open position and which will also close tightly.

A further object of the invention is to produce a Venetian blind of such construction that the openings usually provided in the slats for the lifting cords can be entirely dispensed with.

Another object is to produce a Venetian blind of such construction that the tilting cords can be made of round material, if desired, and in which the lifting cords can be of very small diameter so as to be practically invisible when the blind is in full open position.

A further object of this invention is to produce a Venetian blind of such construction that the slats can readily be unhooked from the lifting cords along one edge to facilitate cleaning.

A further object of the invention is to produce a Venetian blind provided with an especially constructed hinge for effecting a connection between the slats and the tilting cords.

The above and other objects that may become apparent as this description proceeds are attained by means of a construction and an arrangement of parts that will now be described in detail, and for this purpose reference will be had to the accompanying drawing in which the invention has been illustrated in its preferred form, and in which:

Figure 1 is a perspective view showing the blind in open position;

Figure 2 is a section taken on line 2—2, Figure 1, and shows the open position of the blind in full lines and a partially collapsed position by broken lines;

Figure 3 is a side elevation of a slat taken adjacent one end thereof showing the same tilted into a vertical position;

Figure 3a is an end view of the slat shown in Figure 3;

Figure 4 is a plan view of a hinge member showing the blank after it has been pressed into shape and before it has been bent;

Figure 5 is a top plan view of a hinged member;

Figure 6 is a view showing the hinge member in place on a tilting cord;

Figure 7 is a fragmentary view showing the

hinge member assembly of Figure 6 operatively connected to one of the slats;

Figure 8 is a view similar to that shown in Figure 5, but shows the tilting cord directly opposite from that shown in Figure 7; and

Figure 9 is a view showing the position of the parts before the slats are disconnected for cleaning.

In the drawing reference numeral 10 designates 10 a tilting board whose ends are provided with trunnions 11. These trunnions are journalled in bearings in a bracket which has not been shown because the arrangement is old and well known. Reference numerals 12 and 13 represent pulleys 15 that are mounted on the supporting brackets and about which the lifting cords 14 and 15 pass. Secured to the end of trunnion 11 is a cross piece 16 from the ends of which pull cords 17 extend downwardly. The ends of the lifting cords 13 20 and 14 pass through a clamping pulley of the usual type, which has been designated by reference numeral 18. At the bottom of the blind is a board or similar member 19, which is somewhat heavier than the slats which have been designated 25 by reference numeral 20. The slats are all the same size and shape and in the present embodiment they have been shown as made from sheet metal. The edge of a slat along the right side when viewed as in Figures 2 and 9 is rolled downwardly and inwardly, as designated by reference numeral 21 in Figure 7. At spaced intervals notches 22 are provided in the rolled edges. The other edges of the slats are bent reversely into U-shape as shown by reference numeral 23, in 30 Figures 2 and 9. The ends of the slats are provided with notches 24 for the reception of the lifting cords. It will be observed from Figures 3 and 3a that the metal on opposite sides of the notches 24 has been offset in opposite directions 35 for the purpose of providing as nearly as possible, a straight path for the lifting cord when the blind is in folded or closed position as shown in Figures 3 and 3a. The lifting cords may be of the usual construction and have their lower ends secured 40 to the ends of the bottom slat 19 at points 25. For the purpose of supporting the slats and tilting them, a plurality of pairs of tilting cords like those 45 designated by reference numerals 26 has been provided. The upper ends of the tilting cords are secured to the tilting board 10 at points 27 and the lower ends are attached to the bottom board 19 at points 28. For the purpose of effecting a 50 connection between the slats and the tilting cords, the latter are provided with hinge members which will now be described.

In the present embodiment the hinge members are formed from short pieces of wire which have been flattened so as to provide a central flat portion 29 that is connected with the round trunnions 30 by means of the inclined surfaces 31. The blanks shown in Figure 4 are bent around a suitable mandrel into the shape shown in Figure 5 in which the trunnions 30 extend axially and in opposite directions. Before the blank is moved to the position shown in Figure 5, it is positioned on a lifting cord and adjusted to the right position, after which it is closed, whereupon the hinged member will become firmly attached to the tilting cord. The hinge members are connected with the slats along the edge having the roll 21 by first opening the latter slightly at each side of the notch 22 and inserting the trunnions into the opening in the roll whereupon the material is then pressed back into position. This forms a hinge that has sufficient rotary movement to accommodate either position of the slats and which is not detachable. Along the opposite side of the slats where the material is bent into the U-shaped fold 23 the hinge members are readily inserted, either by first offsetting the tilting cords as shown in Figure 9, or by merely bending them in a manner quite apparent. The U-shaped openings marked 23 need not extend the entire length of the slat, but must be left in that position adjacent the notches 22, so as to permit a ready detachment. The material between these U-shaped portions may be round, as indicated by reference numeral 21.

It will be apparent that with this construction, the slats do not require any punched holes in the center to accommodate the lifting cords and only two of the latter have been shown or are required. The tilting cords serve to support the slats at spaced intervals and since the tilting cords are connected with the slats by the hinged connection described, the old ladder construction is not required. It is the intention to make the lifting cords 15 out of transparent plastic, such as is now employed for men's suspenders and in many other places, and, due to the fact that they can be positioned quite close together and to the further fact that such plastic is strong, the tilting cords can be made of comparatively small diameter and since they are also made from transparent material, they become practically invisible. When the blind is turned with the slats in horizontal position, the blind becomes very inconspicuous when compared with the older constructions having the wide ribbon lifting cords.

When the blind needs to be washed or cleaned, the parts are first moved into the broken line position shown in Figure 2, which corresponds to the position shown in Figure 9. When in this position the slats can readily be detached from the lifting cords on one side and allowed to hang vertically as indicated at X in Figure 2. When in this position they can be readily brushed and it is also possible to clean them by means of a hose, where the blinds are so positioned that the water resulting from this method of cleaning will not be objectionable.

With this construction the slats can be perfectly straight transversely and the folds or rolls along the edges can be very small, thereby reducing to a minimum the obstruction when viewed in the

plane of any slat. The means for tilting and for lifting and anchoring has been shown more or less diagrammatically as the means shown is old and well known, with this exception that the lifting cords are positioned at the ends of the blinds only instead of being distributed throughout their length in the usual manner.

Blinds constructed in the manner described and shown on the drawing are more practical and more attractive in their finished form than the ordinary blind.

Attention is directed in particular to the construction employed for effecting a hinged connection between the slats and the tilting cord and to the fact that the slats can readily be detached from the cords on one side for cleaning. When detached they will hang in overlapping position and cannot be opened without first reattaching them, which assures that they cannot be opened accidentally where a room is to be darkened for a considerable time. The slats can be made from any suitable metal or alloy and also from fiber or plastic, and when aluminum or other light weight metals or alloys are used, the blind will be of light weight.

Having described the invention what is claimed as new is:

1. In a Venetian blind having a plurality of slats, and means for supporting and tilting the slats comprising a plurality of pairs of cords, the cords of each pair being positioned at transversely opposite points, means for effecting a hinged connection between the cords and the slats comprising hinge members secured to the cords, said members having a portion encircling the cords and a portion projecting laterally therefrom, the lateral portion having oppositely extending trunnions, the slats having a notch corresponding to each cord, the sides of the notches having axially aligned openings for the reception of the trunnions.

2. A venetian blind comprising, a plurality of slats, means for supporting the slats in spaced parallel relation, said means comprising a plurality of pairs of combined supporting and tilting cords, the cords of each pair being positioned at transversely opposite points and means for effecting a pivotal connection between each cord and the adjacent edge of the slat comprising a hinge member having an intermediate portion thereof encircling the tilting cord and provided with oppositely extending aligned trunnions, the slats having notches in their edges for tilting cords, the sides of the notches having openings for the reception of the trunnions.

3. A venetian blind comprising a plurality of metal slats, each provided in its edges with oppositely positioned notches, the sides of the notches having axially aligned openings, a plurality of tilting and slat supporting cords arranged in pairs, each pair being positioned on opposite sides of the slats, one at each of the oppositely positioned notches, and means for effecting a tilting connection between the slats and the cords comprising a hinge member having one end provided with an opening through which a tilting cord extends, the other end having oppositely extending aligned trunnions for engaging in the openings in the sides of a notch.

WILLIAM M. DUNN.
